UNITED STATES PATENT OFFICE.

NUNZIO RICCARDO DI CRISTINA, OF PALERMO, ITALY.

APPARATUS TO RENDER POSSIBLE THE INHALATION OF MEDICINAL POWDERS.

Application filed August 13, 1924, Serial No. 731,736, and in Italy August 17, 1923.

The purpose of my invention is to render possible to the respiratory organs the direct intaking of a pulverulent medicamented mixture that furnishes to the human organism the means to remedy a deficiency of calcifying and mineralizing salts, so as to facilitate the calcification of pulmonary lesions and the normalization of the calcic metabolism in exhausting diseases; and so that 10 the pulverulent mixture reaches the main respiratory organs and does not stop in the primary respiratory passages, it is inhaled in a current of compressed air that is warm and dry. My apparatus supplies a medicamented mixture, under pressure, to the patient as he inhales, so as to reach to the parts of the lungs that have tended to stop functioning. Preferably, the pressure is due to compressed air, and the air is supplied dry 20 by being heated.

I attain these objects by means of the apparatus illustrated in the accompanying drawings, in which:

Fig. I is a view of the apparatus as designed for institutions, hospitals, and other places where a plurality of patients can be simultaneously treated.

Fig. II is a view of a smaller type of apparatus designed for private use.

Referring to Fig. I, the apparatus consists of a pedestal with an electric motor and apparatus for the compression of air, with electric resistances for the warming of same, and an air chamber, quadrilateral or polyhedral in shape, in which is placed the reservoir for the powders, leading to the charging tube and to the distributing tubes.

The operation of the apparatus is described with reference to Fig. I and to the parts indicated thereon by letters, as follows:

"A" is a metallic tube through which the pulverulent material which is to be inhaled is forced into the surrounding atmosphere, if this method is preferred to that of direct inhalation by means of the mouthpieces. The said tube "A" passes through "B", the distribution chamber, and is also used for the purpose of charging, i. e., permitting 50 the filling of, "C", the reservoir for the powders, which connects with "B".

"B" is the distribution chamber and is equipped with outlets for the passage of the powders to the mouthpieces, from which the

patient inhales the powders perfectly an- 55 hydric with warm, dry, compressed air.

"C" is the reservoir for the powders, with very small holes to permit the passage of the compressed air, so that the powders are forced into "B", the distribution chamber 60 and from there to the mouthpieces.

"D" is the air chamber, which accumulates the necessary quantity of warmed air to feed the mouthpieces.

"E" are peep holes, hermetically closed by 65 means of clamp screws, to permit thermometric observations and for controlling the operation of the apparatus. Inside and over each window there is a hook to which may be hung a thermometer.

"F" is the air and heat regulator.

"G" is the air compressor.

In the operation of this form of apparatus, air is drawn into the apparatus and compressed by the air compressor, and is 75 warmed to any desired temperature and dried by electric coils or other suitable apparatus. The warm dry compressed air accumulates in the chamber "D", subject to 80 control by the air and heat regulators at "F", and passes from "D" through the small apertures in the reservoir "C", which reservoir is filled with a suitable medicated powder or other substance. The air pressure drives the powder into the distribution 85 chamber "B", and from "B" the mixture of air and powder is driven out through the tubes to the mouthpieces, from which the patient inhales the mixture. Suitable cocks 90 control the passage of the mixture from the distribution chamber "B" to the mouthpieces.

If desired, the mixture can be driven directly from "C" through the tube "A" into the surrounding atmosphere, if this method of use is preferred to that of direct inhalation through the mouthpieces.

The smaller apparatus shown in Figure II, is substantially similar in operation to the larger machine. It consists essentially 100 of a motor and compressor which forces the air through a tube, where it becomes warmed, into a reservoir, from which the powders are expelled through a mouthpiece.

This apparatus may be described by reference to its parts, which are lettered as follows:

"A" is a tube for the outlet of the mixture,

and is provided with a mouthpiece for conveying the mixture to the patient.

"B" is a reservoir for the medicated powders, which is perforated to allow the passage of compressed air.

"C" is an air chamber which accumulates the necessary quantity of warm air to force the powder through the tube "A".

"D" is an air compressor with apparatus 10 for warming the air.

"E" is a clamp screw to regulate widening or narrowing the aperture in chamber "C" and controlling the outlet of the mixture from tube "A".

15 Having thus described my invention, I claim:

An apparatus to render possible the inhalation of medicinal powders comprising a blower for compressing air, apparatus for heating air, a chamber for storing a relatively large quantity of compressed and heated air, a medicinal powder container, having a plurality of minute orifices therein, and positioned to so hold powder as to be carried away with compressed air from said chamber, a distribution chamber positioned to receive carried away powder and air, and controllable discharge means from said distribution chamber.

Signed at Palermo, Italy, this 24th day of July, A. D. 1924.

NUNZIO RICCARDO DI CRISTINA.
